Primary Examiner — Kevin K Rudzinski*Assistant Examiner* — Kathleen L Jones(74) *Attorney, Agent, or Firm* — The Compton Law Firm, P.C.; Scott D. Compton(57) **CLAIM**

The ornamental design for a reticle, as shown and described.

DESCRIPTION

FIG. 1 is a front view of a reticle showing my new design with an optical medium provided in broken lines; and, FIG. 2 is another front view of the reticle.

The broken lines showing of the optical medium in the figures is for illustrative purposes only and form no part of the claimed design. The additional broken lines showing the environmental structure seen beyond the reticle in FIG. 2 are for illustrative purposes only and form no part of the claimed design.
